PLAYGROUND CLIMBING DEVICE OR SIMILAR ARTICLE

Morris R. Rudy, Burnham, Pa., assignor, by mesne assignments, to The Singer Company, New York, N.Y., a corporation of New Jersey

Filed Dec. 11, 1967, Ser. No. 9,735

Term of patent 14 years

(Cl. D34—5)

FIG. 1 is a front perspective view of a playground climbing device or similar article illustrating my new design,

FIG. 2 is a top plan view thereof,

FIG. 3 is a front elevation view thereof,

FIG. 4 is a side elevation view thereof as seen from the left in FIG. 3 and is a mirror image of the side elevation view as seen from the right in FIG. 3 (not shown),

FIG. 5 is a rear elevation view thereof, and

FIG. 6 is a bottom plan view thereof.

Those portions shown in broken lines are for illustrative purposes only.

I claim:

The ornamental design for a playground climbing device or similar article, substantially as shown and described.
